COTTON PICKER OF THE SPINDLE TYPE

Robert H. Meier, Des Moines, Iowa, assignor to Deere Manufacturing Co., Dubuque, Iowa, a corporation of Iowa

Application August 8, 1955, Serial No. 526,926

6 Claims. (Cl. 56—41)

This invention relates to improved means for mounting mechanism that is auxiliary to the picking mechanism of a cotton picker of the spindle type. More particularly, the invention relates to means for mounting spindle-moistening means for movement between operating and servicing positions.

A typical cotton picker in which the present design finds its most practical utility is shown in the Thomann and Meier Patent 2,719,394. In a cotton picker of that type, a plurality of vertically spaced apart series or layers of rotating spindles move through individual orbits to perform the picking operation. At a particular zone in each orbit is means for doffing the picked cotton from the respective spindles and at another zone in each orbit is means for applying a moistening agent to the spindle, which process has been found to improve the picking characteristics of the spindles or fingers. In known machines, the moistening means comprises a column on which is supported a plurality of vertically spaced apart moistener members or pads, equal in number to and spaced on the order of the layers or series of spindles, so that each series of spindles will pass through its moistener pad to receive the moistening agent therefrom. The picking mechanism and moistener means is enclosed in a housing and, although access openings with removable closures may be provided, it is very often difficult to reach some of the parts for servicing, replacement and adjustment. According to the present invention, the moistener means, as representative of one type of auxiliary device in conjunction with picking mechanism, is mounted for movement between an operating position and a servicing position. The operating position is the normal position of the auxiliary means when the machine is functioning and this position is relatively remote from the available access door. The means is mounted for shifting between its two positions and releasable securing means, accessible through the access opening, normally holds the means in its operating position. When the releasable means is released, the moistener or other auxiliary means may be swung to a position relatively close to the access door, whereby access thereto may be had through the access opening when uncovered. The invention features a simple and inexpensive construction that may be readily adapted to machines of existing design.

The foregoing and other important objects and desirable features inherent in and encompassed by the invention will become apparent as a preferred embodiment thereof is disclosed in detail in the ensuing specification and accompanying sheets of drawings, the several figures of which will be described immediately below.

Fig. 1 is a fragmentary perspective view of a portion of a typical cotton picker housing.

Fig. 2 is a similar view, but showing the access doors removed.

Fig. 3 is a fragmentary sectional view, on an enlarged scale, as seen along the line 3—3 of Fig. 1.

2

Fig. 4 is a fragmentary sectional view, in part in elevation, as seen along the line 4—4 of Fig. 3.

Those familiar with cotton picker construction as typified by the disclosure in the above noted Thomann and Meier patent will recognize in the drawings a supporting housing A made up of a plurality of upright and horizontal walls. Among these are a bottom or floor 10, a top wall 12, an intermediate wall or ceiling 14 and several upright walls 16, 18 and 20, the last named of which will be hereinafter referred to as a front wall. However, directional designations are for purposes of convenience only and it will be obvious that the parts could occupy positions other than those illustrated and described. The ceiling 14 divides the housing A into upper and lower compartments B and C, and the front wall 20 has access openings 22 and 24 which lead respectively to or are in register with the compartments B and C. During normal operation of the machine, these openings are closed by closure means in the form of doors 26 and 28. Wing nuts 30 and 32 are shown as representative securing means for the doors.

At one side of the housing A is a vertical tube or conduit 34 which forms part of pneumatic conveying means for removing doffed cotton from housing-contained picking mechanism D. This mechanism is of a well-known commercial type utilizing a plurality of series of generally horizontal radially projecting fingers or spindles 36. The angular spacing of the spindles will be apparent from Fig. 3, in connection with which it should be noted that the section of Fig. 3 is such that the top wall 12 does not appear in the figure and a portion of the ceiling or intermediate wall 14 is broken away, so that a part of one of the spindles 36 shows in full lines. The vertical spacing of the spindles 36 will be apparent from Fig. 2.

An auxiliary device, here a moistener means E, is contained within the housing in association with the picking mechanism D. The type of moistener shown here is like that forming the subject matter of the patent to Grossvenor 2,654,204; although any typical moistener could be used if arranged as will be presently disclosed. The herein illustrated moistener comprises an upright shaft 38 of hexagonal or otherwise noncircular section on which a plurality of rubber elements 40 are stacked to form a column 42. The upper end of the column, as at 44, is carried in the ceiling 14 by means of an upper pivotal support F, and the lower end of the column, as at 46, is carried in the floor or bottom 10 by a lower pivotal support G. The ceiling 14 has a circular aperture 48 for receiving a carrier 50 that forms part of the upper support F. This carrier is rigidly but removably secured to the ceiling 14 by a plurality of cap screws 52 (Fig. 3). The upper end 44 of the column 42 is supplied with a moistening agent by means of a suitable conduit 54 and the theory of operation of the moistener means E is that the moistening agent will flow downwardly through the column and will flow thence outwardly through individual branches 56 to column-carried moistener members or pads 58. As best shown in Fig. 4, each pad 58 serves to moisten the spindles in the associated circular series.

The top end portion 44 of the column 42 is circular and is therefore rotatable or angularly movable in the ceiling-carried carrier 50. The same characteristic is true of the lower pivotal means G; although, the detailed construction of the two supports is somewhat different. Nevertheless, these details are immaterial. In normal operation, the angular position of the column will be such that the pads or members 58 project rearwardly or in set-back relationship to the front wall 20, which position is shown as position H in Fig. 3. In this operating position, the pads are cooperative with

the spindles 36, which themselves represent picking mechanism portions that are relatively remote from the front wall 20. It will thus be seen that the servicing of the pads 58 in position H would be somewhat difficult if the only access thereto is through the lower compartment access opening 24. Normally, the construction of the housing A is such that access cannot be otherwise provided. However, any difficulties previously experienced are eliminated by the present invention, because of the bi-positionable characteristic of the moistener means E. This feature results from the use of the upper and lower pivotal supports so that, in conjunction with releasable securing means I, the moistener means E may be turned so that the pads move from position H to a servicing position J (Fig. 3). The servicing position places the pads 58 relatively close to the front wall 20 and removal of the doors or closure means 26 and 28 permits ready access to the interior of the compartments, and especially to the service-positioned pads 58.

The releasable lock at I is preferably accomplished by the provision on the top end 44 of the column 42 of a lockable portion in the form of a vertical groove 60 which, when the moistener E is in position H, registers with a groove 62 in the carrier 50. An L-shaped pin 64 is dropped into the aligned or registered grooves and receives a removable cotter pin 66 to prevent accidental displacement of the pin 64. As will be readily appreciated, it is a simple matter to remove the access doors 26 and 28, after which the operator may reach in through the lower access opening 24 to remove the cotter pin 66 from the locking pin 64. Access to the locking pin is had through the upper access opening 22. After the lock is removed, the moistener E may be swung from position H to position J for servicing, after which restoration to the normal operating position H may be accomplished and that position secured by restoring the locking pin 64 and cotter pin 66.

Features of the invention in addition to those pointed out specifically herein will undoubtedly occur to those versed in the art, as will many modifications and alterations in the preferred embodiment of the invention disclosed, all of which may be achieved without departing from the spirit and scope of the invention.

What is claimed is:

1. In a cotton picker: a supporting housing structure including a floor, a top wall, an upright front wall connecting said floor and top wall, a horizontal intermediate wall extending back from the front wall and dividing the housing into upper and lower compartments, said intermediate wall having an aperture therein set back from the front wall, and said upright wall having upper and lower access openings therein leading respectively to the upper and lower compartments; picking mechanism supported by the structure in the lower compartment, including a plurality of vertically spaced apart picker fingers set back from the upright wall; moistener means in the housing, including a column having a lower end proximate to the floor and an upper end projecting through the intermediate wall aperture and into the upper compartment, said column having thereon a plurality of horizontally projecting moistener members spaced apart vertically on the order of the picker fingers; upper and lower pivotal support means mounting the upper and lower ends of the column respectively on the intermediate wall and floor for angular movement of the column about its upright axis between an operating position, in which the moistener members cooperate with the picker fingers and are relatively remote from the lower access opening, and a servicing position in which said members are proximate to said lower access opening; said upper pivotal support means including a lockable portion exposed to the upper compartment, a releasable lock element in said upper compartment and selectively engageable with and disengageable from said lockable portion to achieve respectively the operating and servicing positions of the column; and removable

closure means adapted for mounting on the housing structure to close the access openings.

2. In a cotton picker: a housing structure having a compartment defined by a floor, a ceiling and an upright wall, said wall having an access opening therein; picking mechanism in the compartment and supported by the structure, including a plurality of vertically spaced apart picker fingers set back from the upright wall; moistener means including a column having a lower end proximate to the floor and an upper end proximate to the ceiling, said column having thereon a plurality of horizontally projecting moistener members spaced apart vertically on the order of the picker fingers; upper and lower pivotal support means mounting the upper and lower ends of the column respectively on the ceiling and floor for angular movement of the column about its upright axis between an operating position, in which the moistener members cooperate with the picker fingers and are relatively remote from the access opening, and a servicing position in which said members are proximate to said access opening; releasable locking means for selectively locking the column in its operating position and for releasing the column to swing to its servicing position; and removable closure means adapted for mounting on the housing structure to close the access opening.

3. In a cotton picker: a housing structure having a plurality of walls defining a compartment, one of said walls having an access opening for said compartment; picking mechanism in the compartment, including a portion relatively remote from the access opening; auxiliary means supported by the housing structure in the compartment, including a support proximate to the access opening and a member projecting from the support in an operating position proximate to the picking mechanism portion and thus relatively remote from the access opening; means movably mounting the support on the housing structure for shifting of the member relative to the picking mechanism to a servicing position proximate to the access opening; means releasably securing the auxiliary means in its operating position; and removable closure means adapted for mounting on the housing structure to close the access opening.

4. In a cotton picker: a housing structure having a plurality of walls defining a compartment, one of said walls having an access opening for said compartment; picking mechanism supported by the housing structure in the compartment, including a portion relatively remote from the access opening; auxiliary means in the compartment, including a support proximate to the access opening and a member projecting from the support in an operating position proximate to the picking mechanism portion and thus relatively remote from the access opening; means movably mounting the support on the housing structure for shifting of the member relative to the picking mechanism to a servicing position proximate to the access opening; and means on said auxiliary means for releasably securing the auxiliary means in its operating position.

5. In a cotton picker: a supporting housing structure having a floor, a top wall, an upright front wall connecting said floor and top wall, a horizontal intermediate wall extending back from the front wall and dividing the housing into upper and lower compartments, said intermediate wall having an aperture therein set back from the front wall, and said upright wall having upper and lower access openings therein leading respectively to the upper and lower compartments; picking mechanism supported by the housing structure in the lower compartment, including a plurality of vertically spaced apart picker fingers set back from the upright wall; auxiliary means in the housing, including an upright support having a lower end proximate to the floor and an upper end exposed to the upper compartment through the intermediate wall aperture, said support having thereon a plurality of hori-

zontally projecting members spaced apart vertically on the order of the picker fingers; upper and lower pivotal means mounting the upper and lower ends of the support respectively on the intermediate wall and floor for angular movement of the support about an upright axis between an operating position, in which the members cooperate with the picker fingers and are relatively remote from the lower access opening, and a servicing position in which said members are proximate to said lower access opening; said upper pivotal means including a lockable portion exposed to the upper compartment; and a releasable lock element in said upper compartment and selectively engageable with and disengageable from said lockable portion to achieve respectively the operating and servicing positions of the column.

6. In a cotton picker: a housing structure having a compartment defined by a floor, a ceiling and an upright wall, said wall having an access opening therein; picking mechanism supported by the structure in the compartment, including a plurality of vertically spaced apart picker fingers set back from the upright wall; moistener means in the housing, including a column having a lower end proximate to the floor and an upper end proximate

to the ceiling, said column having thereon a plurality of horizontally projecting moistener members spaced apart vertically on the order of the picker fingers; upper and lower pivotal support means mounting the upper and lower ends of the column respectively on the ceiling and floor for angular movement of the column about its upright axis between an operating position, in which the moistener members cooperate with the picker fingers and are relatively remote from the access opening, and a servicing position in which said members are proximate to said access opening; and releasable locking means for selectively locking the column in its operating position and for releasing the column to swing to its servicing position.
